FULL FASHIONED TEXTILE KNITTING
MACHINE

George Richard Meinig and August C. Pauli,
Reading, Pa., assignors, by mesme assignments,
to Karl Lieberknecht, Inc., a corporation of
Pennsylvania

Application November 27, 1934, Serial No. 754,983

9 Claims. (Cl. 66—127)

The present invention relates generally to textile knitting machines known as straight or flat knitting machines, which are especially adapted for the manufacture of full fashioned stockings. More particularly, this invention, being directed to improvements in the mechanism disclosed in copending application, Serial Number 668,966 filed May 2, 1933, in the names of August C. Pauli and Otto C. Hamel, contemplates means devised to produce the knitted fabric in accordance with the method disclosed in copending application, Serial Number 662,501 filed March 24, 1933 in the name of Ernst Richard Meinig, and pertains to knitting machines of the character mentioned wherein are provided means for selectively laying one of several threads in predetermined order upon the needles to form throughout the length of the stocking successive courses of separate and individual threads, thereby overcoming the disadvantages caused by the inherent characteristics of real silk yarn, such as unevenness in the thickness of the thread, by eliminating the formation of "rings" or "shadows" in accordance with the recently developed method disclosed in the United States Patent No. 1,969,307, the product of which has become known in the trade as "ringless" stockings.

In carrying out the method aforesaid into practice, considerable difficulties have been experienced in the adequate selection and control of the carrier rods so that the movement thereof could be had in proper predetermined sequence to produce the desired results. Means for selecting and controlling the carrier rods have been devised but, because of their complicated structure and involved assembly, they have proven unsatisfactory, if not wholly impracticable.

It is therefore one of the principal objects of this invention to provide a simplified device for accurately selecting and controlling the proper carrier rod to move the same in time with the operation of the knitting machine in order that each of a plurality of threads utilized in the making of "ringless" fabric by the Multi-Carrier Method may be drawn into desired sequence by its respective carrier over the knitting section of the machine for the formation of the course, said device being so constructed that it may be readily assembled and mounted on the ordinary knitting machine without necessitating any material changes therein.

It has been found necessary, when selecting certain carrier rods for operation when others remain inoperative, to lock those carrier rods remaining in inoperative position because, otherwise, the unavoidable jarring and vibration of the machine in operation cause the disengaged carrier rods to move, resulting in displacing the latter, thus rendering almost impossible the proper engagement between the carrier rods and

the selecting device and, further, interfering with the proper laying of the yarn in relation to the needles.

Accordingly, another important object of the invention resides in the provision of means mounted on the knitting machine in addition to the carrier rod selecting and controlling device and capable of automatically locking the carrier rods when at rest and releasing the same when about to be engaged by the selecting device for actuation, said locking-releasing means being operatively associated with the selecting device whereby both mechanisms will work in unison, thus assuring a timed action therebetween. 5

The invention further seeks to provide a novel combination and association of elements cooperating to form series of complete courses and partial courses having interlooping engagement, whereby to produce a finished "ringless" fabric 10 wherein partial courses are knitted into the fabric for reinforcing the same. 15

The present invention also includes among its characteristic features the provision of a mechanism cooperating with the carrier rod selecting device and locking-releasing means, and operable 20 to cause the travel for certain carrier rods over a predetermined number of needles or a partial course distance, thus bringing a portion of the thread utilized for the formation of one course into the following course or courses made from 25 separate threads, whereby said thread portion from one course may interloop a series of loops in the following course or courses to constitute a strip of reinforced wales in those sections of the fabric normally in need of reinforcement, 30 such as the selvedge edges and the heel tabs. 35

Besides the foregoing objects, our invention aims to provide a novel construction and association of elements capable of being applied 40 readily and practically to the type of textile machines now commonly in use, and, coacting to obtain a silk stocking wherein "rings" or "shadows" are eliminated in accordance with the Multi-Carrier Method of knitting, and cofunctioning to produce in such stockings unique reinforced portions constituted by interlocking the threads employed for the formation of the successive courses and, consequently, without necessitating the introduction of an additional reinforcing thread into the fabric, resulting in a 45 stronger stocking of better appearance. 50

Other important objects and advantages of the invention will be in part obvious and in part pointed out hereinafter.

In order that the invention and its method of 55 operation may be readily understood by those persons skilled in the art, we have in the accompanying drawings and in the detailed description based thereupon, set out several possible embodiments of the same. In these drawings: 60

Figure 1 is a fragmentary plan view of a full fashioned knitting machine, showing our invention applied thereto.

Figure 25 is a greatly enlarged diagrammatic illustration of the formation of the loops in the knitted fabric.

Figure 26 is a diagrammatic representation of 60 the leg of a full fashioned stocking in flat state made on a machine constructed in accordance with the invention.

Figure 27 diagrammatically shows the three carriers in operation.

Figure 28 illustrates a further modification 65 represented in Figures 3 and 5.

Figure 29 is an enlarged face elevation of the same, with certain parts taken away.

Figure 30 is a partial top plan view of the 70 reciprocating means utilized for displacing the locking device.

Referring more particularly to Figures 25 and 26 of the drawings, we have shown a knitted stocking blank A having a plurality of sections throughout its area, as more clearly illustrated

in Figure 25, where three sections have been shown and designated by the reference characters S1, S2 and S3.

Each knitted section consists of a course B, a course C, and a course D, the course B being 5 formed by a separate independent thread B', the course C being formed by an independent thread C', and the course D being formed by an independent thread D'. For clarity, the thread B' is shown in black and white, the thread C' 10 in solid white, and the thread D' in solid black.

It will be noted that the thread B' forming the course B in section S1 forms the course B in section S2; the right selvedge stitch forming the connection. The thread B' is also used 15 to knit the course B of section S3, the left selvedge stitch making the connection, and this knitting of the first course is continued throughout the entire area of the blank. The thread C' forming course C of section S1 also forms the 20 courses C of sections S2 and S3; the thread D' of course D of section S1 is also used to form courses D of sections S2 and S3. Thus it will be appreciated that each individual thread systematically forms the identical course in each section 25 through the entire area of the stocking blank.

According to the invention, the fabric A is to be reinforced at certain portions thereof, such as the selvedge edges E and F and heel tabs H. For this purpose, partial courses and complete 30 courses are combined, the loops of the partial courses having interlooping and overlapping engagement with the loops of the complete courses, as will more clearly appear from Figure 25. This is accomplished by carrying the thread 35 utilized for the formation of a complete course over the following complete course or courses, whereby a series of auxiliary loops G are formed simultaneously with the knitting of said following course or courses to overlap several adjacent loops of the regular courses, as indicated at K, thus constituting a strip of reinforced wales R at the selvedge edges E and F while the intermediate portion of the blank A is knitted with 40 series of plain loop wales P.

The fabric constructed as above defined is obtained by means of a combination of specially devised mechanisms cooperating to produce the desired results in a manner which will be apparent as the following detailed description progresses.

With reference to the drawings wherein like characters of reference will designate corresponding parts throughout and illustrating the mechanisms for producing the type of fabric 55 above defined, it will be noted that we have shown only those parts of a full fashioned hosiery knitting machine which are essential to the proper comprehension of the present invention, the knitting machine itself being of the usual standard construction well known in the art; also, whereas the drawings show portions at one end of the usual knitting machine, it is to be understood that similar duplicate parts are provided at the opposite end and operate in like manner.

In the drawings, there is represented the usual frame 1 having the front beam 2, back beam 3, center bed 4, cam shaft 5, and the customary rock shaft 6. The knitting section of the machine, designated in its entirety for convenience 70 by the reference character 7, is mounted in a general way about the center bed 4 of the frame 1 and essentially comprises the needle bar 8, knock over bit 9, sinkers 10 mounted in their support 11, catch bar 12, jacks 13, pivoted to the 75

5 jack bed 14 and acted upon by the slur cock 15, the latter being slidably mounted on the cock box bar 16 and moved thereon through the connecting bar 17 which is, in turn, reciprocated by action of the usual "Coulier motion" of the machine. The thread or yarn is fed to the knitting section of the machine by the carriers 18 depending from the carrier rods 19 mounted for reciprocation in the carrier rod bracket 20.

10 The relative position, function, and operation of these elements of the knitting section 7, as above defined, are well understood by those skilled in the art and, consequently, a more detailed description thereof is dispensed with here-
15 inasmuch as the knitting operation is not changed in the machine by the application of this invention thereto.

20 In the aforesaid method of knitting stockings of the "ringless" type, it has been found preferable to use three carriers (or more), each having a separate thread, and each being adapted to be successively moved in repeated sequence over the knitting section of the machine to lay its respective thread for the formation of one 25 of every three (or more) courses. The present invention does not vary from this generally preferred conception and, consequently, there have been shown in the drawings three carriers respectively designated by the reference characters 30 18a, 18b, and 18c, each connected to a distinct carrier rod as shown at 19a, 19b, and 19c.

As stated, the invention resides in the combination and association of mechanisms cooperating to produce a particular type of full fashioned stocking fabric and may be stated to include:
35 1. The carrier rod selecting mechanism; 2. The carrier rod locking and releasing mechanism; and 3. The carrier lock displacing mechanism. For clarity and convenience, each cooperating mechanism, as above identified, will be described 40 in the order stated.

Carrier rod selecting mechanism

According to the present invention, as more 45 clearly shown in Figure 2, a cam 21 is rigidly fixed to the cam shaft 5 to revolve therewith and acts upon a roller 22 suspended adjacent said cam 21 by means of a pendulous lever 23 having one end formed with a bearing 24 engaged upon the rock 50 shaft 6 of the machine and the other end provided with a hook-like extension 25 for engagement with a coil spring 26 suitably connected, for instance, by means of a bracket 27 to the front beam 2 of the machine frame 1, said spring 55 26 acting to normally maintain the roller 22 in close contact with the peripheral surface of the cam 21.

Adjustably connected to the lever 23 through a collar 28 is a bent rod 29 extending to the rear of 60 the machine and having its free end 30 projected beyond the back beam 3 of the frame 1.

Supported upon said back beam 3 by means of brackets 31 and bearings 32 is a horizontally disposed stub shaft 33 having keyed to a portion 65 thereof a ratchet wheel 34 engageable with a ratchet pawl 35 carried by a plate 36 loosely mounted upon the stub shaft 33 and arranged concentrically with respect to the ratchet wheel 34. The loose plate 36 is maintained in position 70 upon the stub shaft 33 by means of a collar 37 rigid with said shaft. The loose plate 36, further, is provided with a depending projection 38 which affords means for connection through a suitable coupling 39 to the extending extremity 30 of the 75 cam operated rod 29.

For the purpose of normally holding the stub shaft 33 with its ratchet 34 against accidental rotation, there is fixed to said shaft a toothed disc 40 adapted to have locking engagement with a catch 41 suspended over the peripheral surface 5 of said disc 40 from a rod 42 engaged at one of its extremities with a coupling 43 pivoted to a supporting bracket 44 fixed to the back beam 3 of the machine frame 1. The remaining extremity of the catch supporting rod 42 engages one 10 end of a coil spring 45 which, in turn, has its opposite end in engagement with a rod 46 extending from the back beam 3 in parallel relation to said catch supporting rod 42. In this manner, the spring 45 urges the catch 41 into 15 locking engagement with the toothed disc 40 and, since said disc is rigid with the stub shaft 33, the latter will be prevented from free rotation in its bearings 32.

Disposed in a plane substantially paralleling 20 that of the stub shaft 33 and rotatably mounted in bearing 47 upon the rear of the machine frame 1 at a point above the back beam 3 thereof, is another shaft 48 connected through a sprocket and chain drive 49 to the stub shaft 33 so that the movement of the latter is transmitted to said shaft 48. A cam 50 is keyed, or otherwise secured, to the shaft 48 to revolve therewith and coacts with a roller 51 to oscillate a lever 52 carrying said roller 51 at its intermediate portion, 30 and pivoted at one of its ends to a bracket 53 extending from the rear of the frame 1. Suitably connected to, and preferably adjustable upon the free end of the lever 52 by means of a coupling 54, or the like, is an upstanding rod 55 provided at its upper extremity with a crank 56 engaging a frame work 57 rockingly supported in standards 58 horizontally above the knitting section 7 of the machine and particularly over the carrier rods 19 thereof.

40 Mounted for longitudinal reciprocating movement on frame work 57 and adapted for transversal sliding movement thereon is a selecting arm 59 engaging a friction box slide 60 through a pivoted fork connecting link 61. The free end 45 of the arm 59 is provided with a catch 62 adapted for selective introduction within the recess 63 of any one of a plurality of catch plates, such as designated by reference characters 64, 65 and 66 respectively secured to the carrier rods 19a, 19b, 50 55 and 19c.

In order to facilitate the proper engagement of the arm 59 with the catch plate of the selected carrier rod, it will appear from Figures 2 and 11, and more particularly so from a comparison between Figures 13, 14, and 15, that the catch plates 64, 65, and 66 are relatively of different sizes so as to lay in stepped formation, thus allowing the unobstructed rocking movement of the arm 59 for the purpose of selecting the desired carrier rod 60 in the manner to be hereinafter more specifically described.

From the association of the elements of the mechanism so far described, it will be understood that with the operation of the knitting machine, 65 the cam 21 fixed to the cam shaft 5 will revolve with the latter and, because of its constant yieldable and frictional engagement with the roller 22, will cause the pendulous lever 23 to swing back and forth and, accordingly, impart a reciprocating motion to the bent rod 29. This motion of the rod 29 oscillates the loose plate 36 about the stub shaft 33 carried in bearing 32 at the rear of the machine frame 1 and thus brings the ratchet pawl 35 into operation for advancing step by step 70 75

to ratchet wheel 34 to impart a partial rotation to the stub shaft 33. The toothed disc 40 being adapted to revolve with the stub shaft 23, it will be understood, forces the yieldably mounted catch 41 to ride on its peripheral surface and fall into successive notches of said toothed disc and, therefore, lock the shaft 33 after each partial rotation thereof. For this purpose, of course, the distance between the notches of the toothed disc 40 is predetermined for timed action with the operation of the ratchet mechanism.

Because of the sprocket and chain drive 49 between the shaft 33 and the shaft 48, the motion of the former is transmitted to the latter thereby actuating the cam 50 thereof, acting through roller 51, to pivot the arm 52. The pivotal movement of said arm 52 alternatively pulls and pushes the rod 55 connected thereto which, due to the crank connection 56 rocks the frame work 57 carrying therewith the carrier rod selecting arm 59.

The camming surface of the cam 50 is designed to present three different points of contact, as represented in Figure 2 by line *a*—*a*, line *b*—*b* and line *c*—*c*, whereby through the intermediate connection referred to, the catch 62 of the arm 61 is successively brought to lay in three distinct horizontal planes, to engage the respective catch plates 64, 65, and 66 of the carrier rod to be selected in the manner illustrated in full and dotted lines in Figure 11 of the drawings.

At this point, it is to be noted that the ratchet arrangement 34—35 and its actuating means including the cam 21 and the main cam shaft 5 are so adjusted that the arc of rotation at each movement of shaft 48 will successively bring the cam spot *a*, *b*, or *c* in contact with roller 51 before cam 50 reaches its resting position. Due to this adjustment the engagement between the selecting arm 59 and the carrier rod to be selected is positively assured. Upon engagement of the selecting arm 59 with the selected carrier rod, the friction slide 60 connected to said arm longitudinally displaces the same on frame work 57 causing the engaged carrier rod to travel over the machine.

Carrier rod locking and releasing mechanism

Affixed to the shaft 48 by means of a coupling 67 is a shaft extension 68 supported in bearing 69 upon the frame 1. The extended portion of the shaft 68 is provided with a bevel gear 70 disposed to engage a key 70a for slidable movement on said shaft and to mesh with a companion bevel gear 71. The gear 71 is coupled through a universal drive shaft 73 to the carrier rod locking means embodied in this invention. Said shaft 73 may be mounted in any suitable manner. For instance, as shown in Figure 31, the shaft is rotatably mounted in a bearing 72 connected to a bracket 72a attached to a sleeve 73a slideable on the narrowing shaft N of the knitting machine. The sleeve 73a is provided with an arm 73b connected to the narrowing nut so that said sleeve, together with bearing 72 will be displaced with movement of said nut. The gear 70 is held in constant mesh with gear 71 by a fork 72b rigid with bearing 72. The locking means designated in its entirety by the reference character 74, through its connection with shaft 48 carrying the cam 50 controlling the action of the carrier rod selector, works jointly with the latter to release the carrier rod to be selected in the manner to be presently described.

The locking means 74 is mounted upon the spindle nut 75 having threaded engagement with

the carrier rack spindle 76 associated with manually operable means 77 and carries the adjustable stop 78 mounted in the controlling members 79 which constitute parts of the usual full fashioned knitting machine.

Referring more specifically to the locking means 74, the details of which will more clearly appear from a consideration of Figures 6 to 10 and Figures 16 to 19, said means comprises a casing 80 arranged upon the rack spindle nut 75 to move therewith through actuation of the manually operable means 77 thereof. The casing 80 has a clear passage, as indicated at 81 disposed in alignment with the carrier rods 19a, 19b, and 19c to allow a free movement of the latter in and out of the casing.

Received freely within the casing 80 is a set of substantially vertically arranged locking plungers 81 corresponding in number to the number of carrier rods used in the manufacture of "ringless" fabric and having at their upper end portion a laterally extended pin 82 engaging a coil spring 83 in turn connected to a suitable point upon the casing 80 as indicated at 84, said spring 83 normally urging the plungers 81 inwardly of the casing 80 to project within the passage 81 thereof and in the path of travel of the carrier rods 19a, 19b, and 19c. These carrier rods are provided with adjustable dogs 85 having a forward inclined surface 86 adapted, when coming in contact with the projected end of the plungers 81 to raise the same against the normal action of springs 83, said plungers 81 subsequently falling into recesses 87 of the dogs 85 to lock the carrier rods. The fall of the locking plungers 81 is limited by means of a pin 88 extending from one side of said plungers and adapted to come in contact with a bar 89 supported horizontally upon the casing 80.

As hereinbefore stated, the unlocking of the carrier rods is to be obtained automatically through operating of the machine for the timely release of the carrier rod to be engaged by the selecting device previously defined. For this purpose, there is rotatably mounted transversely of the casing 80 a stub shaft 90 connected to the universal shaft 73 and thus receiving its rotation from the shaft 68 through bevel gearing 70—71 and said universal shaft.

Affixed to the stub shaft 90 is a set of eccentric cams 91, one for each locking plunger 81, said cams having a trip 91' disposed to engage successively with continued rotation of the shaft 90 a projection or shoulder 92 rigid with the plungers 81 so that the latter are lifted in predetermined sequence to release the desired carrier rod. The successive action of the eccentric cams 91 on each plunger 81 is clearly shown in Figures 17, 18, and 19 from which it will appear that said cams are so interrelated that their trip 91' lie in relatively different radial planes. This relative positioning of the locking plunger releasing cams 91 is such that their action will correspond to and be timed with the actuation of the carrier rod selecting and moving mechanism. The eccentricity of each cam 91 is accurately determined so that it may hold the associated plunger 81 in its elevated position when the corresponding carrier rod is at the opposite end of the machine, as shown in Figure 18, but in order to assure positive action, we allow said plunger to fall prior to the return of said carrier rod which, due to the inclined surface 86 of its dog 85 will raise and guide the plunger in the manner represented in Figure 17 until the continued movement of the rod brings the recess 87 of said dog 85 in alignment with the plunger, 75

whereupon the same is returned to its locking position, as illustrated in Figure 19.

During certain operations of the knitting machine, it may become desirable to render the carrier rod locking means inactive. Accordingly, there is provided on the casing 80 a pivotal handle 93 and a pivotal link 94, said handle and link being relatively spaced and interconnected by an intermediate bar 95 displaceable by actuation of said handle 93 to an upper and lower position, as illustrated in full and dotted lines in Figure 8 of the drawings. It will be understood that when in the upper position (dotted lines) the bar 95 engaging the underside of the pins 88 simultaneously raises all the locking plungers 81, consequently rendering the same inactive with respect to all of the carrier rods, but when in the lower position (full lines) the bar 95 frees the plungers 81 allowing them to function in the manner herein set forth.

From the foregoing, it will be appreciated that the locking means 74 being directly controlled from the shaft 68 forming an extension of the shaft 48 which controls the carrier bar selecting means, is actuated in time with the latter, that is, when the shaft 48 brings the cam 50 to a determined position for predisposing the selecting arm 59 to engage the desired carrier rod, this identical shaft 48 through the connections stated, causes the proper lock-releasing cam 91 to raise the particular locking plunger 81 of the same desired carrier rod, this timed operation being accomplished by preadjusting the cams 91 with respect to the cam 50 and correlating their respective camming action for the purpose intended.

Carrier rod lock displacing mechanism

In accordance with the present invention, the locking device, that is, the casing 80 and the parts associated therewith, is mounted for automatic slidable displacement back and forth over the machine in the general direction of movement of carrier rods for a number of needles.

In order to obtain this desired result, the casing 80 of the locking device may be supported upon the narrowing spindle nut 75 in slides 96 so that said device, as a whole, may be slidably displaced in relation to the spindle nut. To that side of the casing 80 facing inwardly of the knitting machine is attached by means of a connecting bushing or block 97 a pivoting link 98 which, in turn, is pivotally retained within a slot 99 of a rocking crank 100 disposed at right angles to said link 98 and supported onto the side of the spindle nut 75 by bearings 101. One end portion of the crank 100 is extended, as shown at 102 for rigid connection with an inverted L shaped lever 103 positioned at substantially right angles to the body of said crank and normally extending therefrom in a direction diametrically opposed to that of the link 98.

Pivotedly connected by means of a pin 104 to the depending branch 105 of the inverted L shaped lever 103 is a substantially square block 106 having two of its diametrically opposed edges grooved as at 107 for slidable engagement within a substantially rectangular frame work 108 carried by the upper end of a slidably inclined rod 109 supported for reciprocation in a guiding bracket 110 secured to an appropriate part of the machine frame, as indicated at 111.

The rod 109 is adapted to be automatically reciprocated through the normal operation of the knitting machine. For this purpose, as will appear upon referring to Figures 3 and 5, a cam

112 is affixed to the machine cam shaft 5 to rotate therewith. Pendulously suspended from the rock shaft 6 of the machine is a lever 113 having its depending extremity connected to a coil spring 114 attached through a convenient clamp 115 to the front beam 2 of the machine frame 1.

Rotatably mounted at a point intermediate the length of said lever 113 is a roller 116 urged in positive contact with the peripheral surface of the cam 112 by action of the spring 114. A rod 117 articulated to the lever 113 extends in a substantially horizontal position and projects rearwardly of the machine frame 1 to engage a finger 118 rigid with a plate 119 loosely received on a stub shaft 120 supported in bearings 121 bolted to the back beam 3 of the frame 1. The plate 119 further carries a ratchet pawl 122 cooperating with a ratchet wheel 123 keyed or otherwise rigidly secured to said stub shaft 120.

Also affixed to the stub shaft 120 is a cam 124 disposed to act upon a roller 125 carried by a lever 126 rocking in a support 127 extending from the back beam 3 of the frame 1. One end portion of the lever 126 is projected inwardly of the machine to meet the free extremity of rod 109 in order that a pivotal connection therebetween may be had, as is indicated by the reference character 128.

A coil spring 129 connected to a convenient part of the machine frame such as to the underside of the center bed 4, engages the inner end of the lever 126 and thus acts to maintain the roller 125 in constant contact with the peripheral surface of the cam 124.

In order to hold the stub shaft 120 against free rotation, a toothed disc 130 is rigidly secured upon said shaft and adapted for cooperative engagement with the catch 131 carried by an articulated rod 132 having its free end 133 connected to a spring 134, in turn connected to the outer extremity of the roller carrying lever 126.

From the description of the mechanism just defined, it will be understood that the revolution of the cam 112 by its action on the roller 116 causes the pendulously suspended lever 113 to swing back and forth, thus alternately pushing and pulling the rod 117 to actuate the ratchet arrangement 122-123 imparting a stepped rotation to the stub shaft 120.

The cam 124 displaced by rotation of said shaft 120 and in contact with the roller 125 sets the articulated lever 126 in rocking motion, thus reciprocating the rod 109 in its guiding bracket 110. The upward movement of the rod 109 forces the inverted L shaped lever 103 to move angularly from its normal position shown in full line to the position shown in dotted lines in Figure 9. This motion of the L shaped lever 103 rocks the crank 100 which, by means of the pivoted link 98 exerts a pull on the locking device 74 sliding the same upon the spindle nut 75, and therefore displacing the carrier rods held by said locking device for a distance over the narrowing nut 75 of the machine. The locking device may travel for a variable distance of two or more needles, depending upon the adjustment of the actuating mechanism.

It is to be noted that the sliding motion of the locking device 74 is limited to a two or more needle movement by means of an adjustable stop 135 connected to the casing 80 of the locking device, coming to rest against an abutment 136 extending from a portion of the spindle nut 75 into the path of travel of said stop.

A modification of the mechanism for displacing the locking device 74 and the carrier rods held thereby is shown in Figures 20 to 24 inclusive. In this modification, a cam 137 is 5 mounted on the main cam shaft 5 of the knitting machine and acts upon a roller 138 to impart a vertical swinging movement to a horizontally supported lever 139 having one end pivoted to the front portion of the machine frame 1 and its other end extended beyond the back portion 10 of said frame and connected to a coil spring 140 secured to the rear beam 3. The roller 138 is preferably adjustable transversely of lever 139 by means of thumb bolts 141 regulating the 15 position of said roller in a slot 142 cut in said lever 139.

Carried by said lever 139 is an arm 143 preferably disposed to have one extremity in bearing contact with the cam shaft 5 as indicated at 20 144 in the drawing, whereby to restrict the downward motion of said arm. A ratchet pawl 145 is arranged upon the free extremity of the arm 143 and positioned to actuate the ratchet wheel 146 rotatably mounted upon the vertical section of 25 a generally T-shaped member 147 suitably affixed to the machine.

Mounted immediately adjacent one face of the ratchet wheel 146 in the manner more clearly shown in Figure 24 is a pair of undulated wheels 30 148 adapted to rotate with the ratchet wheel 146. Freely mounted upon the opposed ends of the horizontal section of the T-shaped member 147 at substantially right angles thereto is a pair 35 of levers 149 mounted for adjustment in transversal slides 150 by means of thumb bolts 151. The lower end 149' of each lever 149 is bent and rounded for cooperative engagement with the peripheral surface of the undulated disc 148. In this connection, it is to be noted that one 40 lever 149 is associated with one undulated disc 148 while the other lever is associated with the remaining undulated disc, and that undulations of both discs are arranged in staggered relation, that is, the cam projections 148a of one disc 45 are located in alignment with the depressions 148b of the other.

Because of this arrangement, it will be understood that the levers, with rotation of the undulated discs, will rock always in parallel planes. 50 A coil spring 152 interconnects the lower portions of the levers 149 and constantly urges the same against the undulated disc 148.

Also freely supported upon the opposed ends 55 of the horizontal section of the T-shaped member 147 at a point inwardly of the connection of the latter with the levers 149 and transversely adjustable thereon in slots 153 by means of bolts 156 is a pair of upwardly directed arms 155 having tab-like extensions 156 laterally projecting 60 from their outer edges to effect means of connection with the upper end portion of the levers 149, said arms 155 being provided with sets of teeth 157 extending laterally from their inner opposed edges. A coil spring 158 interconnecting 65 the upper free extremities of the arms 155 acts to normally draw the latter towards one another.

Made rigid with the carrier rack spindle 76 by means of locking bolts 159, or the like, is 70 a disc 160 carrying a series of pins 161 uniformly distributed about the circumferential face of the disc to project therefrom in the path of teeth 157 of the arm 155 aforesaid.

In operation of the modification as described, 75 it will be understood that the pivotal movement

of lever 139 through action of cam 137 will displace the ratchet pawl carrying arm 143 thus causing a ratchet wheel 146 to advance for rotating the undulated discs 148.

With rotation of these discs 148, the levers 149 and, through them, the arms 155 are alternately moved to and from the pin carrying disc 160 rigid with the spindle 76. Therefore, the teeth 157 of the said arms 155 are brought in turn to engage the pins 161 of said discs 160 and, consequently, turn the spindle 76 first one way and then the other. The movement of the spindle 76, it will be appreciated, causes the spindle nut 75 (Figure 23) to reciprocate longitudinally of the machine, carrying therewith the carrier rod locking device 74 which, in this particular instance, may be rigidly fixed to said spindle nut.

It is to be noted that at the point of connection between the levers 149 and arms 155, there is preferably provided an inclined slot 162 which affords a more positive and steady engagement of the teeth 157 with the pins 161 due to the wedge-like action at said point of connection.

Also, it will be noted that the variation in the length of movement of the spindle nut 75 together with the locking device 74 which, as hereinbefore stated, may travel over a variable distance of two or more needles, is had by the adjustment of roller 138, levers 149, and arms 155 in the manner previously described.

A further modification of the mechanism adapted to displace the locking device 74 is illustrated in Figures 28 and 29 of the drawings. According to this embodiment, said locking device 74 is mounted upon a spindle nut 75 in a 35 manner similar to that described in connection with Figure 3, that is, the locking device 74 is mounted to slide upon the spindle nut 75.

Secured to one side of the casing 80 is a pair of relatively spaced downwardly directed brackets 163 having bearings 164 receiving a rod 165 and rigidly fixed to the latter by means of bolts 166, or the like. To the free portion of the rod 165 is pivoted a connecting link 167 engaging the lower branch of an angularly bent lever 168, 45 the latter being suitably mounted upon a portion of the machine frame 1 as shown at 169, to rock about a pin 170 extending through the bent portion thereof. The remaining branch of the said bent lever 168 is pivotally attached to a block 171 sliding in an elongated frame work 172 supported upon the upper end of an upstanding rod 173. The rod 173 is mounted for vertical reciprocating movement in a bracket 174 preferably secured to the underside of the center bed 4 of 55 the machine frame 1. The rod 173 is held against rotary movement by means of a block 175 fixed to the lower end of said rod and extending through a slot 176 cut into a plate 177 depending from the bracket 175.

Rigid with the rod 173 and disposed thereon above the guiding bracket 175 is a housing 178 enclosing a bar 179 projecting out of the diametrically opposed ends of said housing and positioned to have one extremity extended over the upper side of the center bed 4 of the machine frame 1. The bar 179 which is preferably of rectangular cross sectional formation to prevent its rotation relative to the housing 178 may slide freely in the latter and is normally urged towards said center bed by means of a spring 180, effecting a yieldable connection between the housing and the remaining extremity of the bar. That extremity of the bar 179 extending adjacent 75

the center bed 4 has a rounded extension to support a roller 181.

Preferably disposed to slide upon the upper face of the center bed 4 and positioned immediately below the roller 181 is a flat bar 182 standing on edge and having one end twisted upon itself, as represented at 183, in order to parallel the slur cock bar 17 for rigid connection thereto while the free end of the bar 183 is 10 downwardly tapered to provide a gradual inclined surface 184 over which the roller 181 may ride.

Suitably secured to the outer face of the said bar 182, for instance by means of screws 185, is a bar section 186 likewise having a tapered end 15 providing an inclined surface 187 similar to inclined surface 184 but on a plane different from the latter.

Upon the exposed face of the bar section 186 is a block 188 gradually reducing in width and 20 terminating with a thin edge near the end of said bar section. A roller 189 suspended by a pin 190 from the bar 179 is adapted to come in contact with the reducing face of said block 188. A spring 191 conveniently connected to the roller 25 pin 190 and to a portion of the machine frame, constantly urges the roller 181 towards the bar 182.

From the foregoing description of this latter modification, it will appear that the bar 182 being 30 connected to the slur cock bar 17 will reciprocate therewith during the operation of the knitting machine. Upon movement of the bar 182 in a direction towards the roller 181, said bar comes in contact with said roller and forces the same 35 to ride up the inclined surface 184 thus raising the rod 173. This motion of the rod 173 rocks the angularly bent lever 168 which then exerts a pull upon the link 165 and, with it, slide the locking device 74 by means of the connecting brackets 163.

With the continued movement of the bar 182, the roller 189 will come to bear upon the block 188 thus forcing the yieldably mounted roller carrying bar 179 to move against the action of 40 its spring 180 and causing the roller 181 to fall on the inclined surface 187 of the bar section 186. Therefore, when the bar 182 is withdrawn with the retracting movement of the slur cock bar 17, the roller 181 will ride down said inclined 45 surface 187 and allow the rod 173 to return to its original position. The downward motion of the rod 173 through the connection mentioned pushes the rod 165 to slide the locking device 74 back to its original position.

The distance to be traveled by the locking 50 device may be regulated by adjusting the bar section 186 in relation to the bar 182. For this purpose, a slot 192 is cut into said bar section 186 at its point of connection with said bar 182, so that the former may slide upon the latter when the securing screws 185 or the like, are loosened. It will be understood that the adjustment of the bar section 186 brings its inclined 55 surface 187 nearer to or farther from the inclined surface 184, and, consequently, the motion of the rod 173 is decreased or increased, causing the locking means 74 to slide for a lesser or greater distance.

Referring again to Figures 25 and 26, the laying 60 of the threads B1, C1, and D1 to form the courses in the repeated sections of the stocking blank is had through the operation of the carrier bar selecting mechanism in the manner heretofore described, particularly with reference to 65 Figures 2 and 4, and acting to displace the carriers 18a, 18b, and 18c. As diagrammatically illustrated in Figure 27, the selecting mechanism operates so that at all times one of the three carriers is at one end of a knitting section of the machine, whereas the remaining two carriers are 5

at the opposite end thereof.

In this position, the first carrier, that is the one carrier at one end of the knitting section, is held by the associated locking device inwardly of the knitting section, said carrier having been 10 advanced previously for a distance corresponding to a certain and determined number of needles through operation of said locking device in the manner heretofore explained, while the second and third carriers, that is the two carriers 15 at the opposite end of the knitting section, are held by the corresponding locking device at the extreme outer portion of the machine.

It is to be noted that during the following movement of the mechanism, the second and 20 third carriers at one end of the knitting section are caused to travel simultaneously for a distance equaling a determined number of needles. Upon reaching that determined position, the unselected carrier, say the second carrier, is stopped and 25 held stationary, but the selected carrier, say the third carrier, is transported to the opposite end of the knitting section where it meets with the first carrier locked in advanced position at that 30 end of the section. These two carriers, that is the first and third carriers, are then retracted together to the extreme adjacent portion of the knitting section to be subsequently moved in the same manner just now described. In this latter 35 instant, however, the third carrier is locked in advanced position while the first carrier is displaced to the opposite end of the knitting section. At the next repeated carrier motion, the first carrier remains at one end of the knitting section while the second carrier is displaced to the opposite 40 end of the knitting section.

In other words, each of the three carriers, in accordance with the present invention, is alternately displaced from one end of the knitting section to the other, but both carriers at one end 45 of the section are simultaneously displaced for a certain number of needles at the incoming and outgoing motion of the selected carrier.

The simultaneous travel of the carriers for a 50 number of needles causes the knitting of series 55 of overlapping loops G at the selvedge edges of the stocking blank A by bringing a portion of the thread utilized for the formation of one course into the following two courses made from separate threads. In this manner, the strip of reinforced wales R is made at the selvedge edges E and F, while throughout the intermediate portion of the blank A the series of plain loop wales P is formed.

As pointed out, the particular showing made 60 illustrates each section as consisting of three knitted courses, each independently formed from an independent thread, but it is to be understood that each section may be of any desired number 65 of courses formed from any desired number of threads. Likewise, it is to be understood that the invention is not to be limited to the particular embodiments disclosed herein, but that the invention is capable of considerable modifications and those modifications which come within the 70 scope of the claims are to be considered within the spirit of the invention.

What we claim is:

1. In a flat knitting machine, a plurality of carrier rods, a mechanism for selectively engag- 75

ing any one of said rods and moving the same upon the machine, a mechanism for locking the unselected rods, a mechanism for automatically displacing said locking mechanism and the rods held thereby with the movement of the selected rod for a distance of the length of travel of the latter, said locking mechanism including means associated therewith and operating in unison with said selecting mechanism for releasing the carrier rod to be selected.

2. In a flat knitting machine, a plurality of carrier rods, a cam shaft, a mechanism controlled from said cam shaft for selectively engaging any one of said rods and moving the same upon the machine; a mechanism for locking the unselected rods and including means operatively connected to said carrier rod selecting means to work in unison therewith for releasing the carrier rod to be selected, and a mechanism also controlled from the cam shaft for automatically displacing said locking mechanism and the rods held thereby with the movement of the selected rod for a distance of the length of travel of the latter.

3. In a flat knitting machine provided with a cam shaft and a spindle nut, a plurality of carrier rods, a mechanism for selectively engaging any one of said rods and displacing the same over the machine, means mounted upon the spindle nut and movable therewith, said means adapted for locking the unselected carrier rods, and means controlled from the cam shaft and engaged with the spindle nut for automatically actuating the latter, thus displacing the locking means together with the carrier rod held thereby, for a distance of the length of travel of the selected carrier rod.

4. In a flat knitting machine, the combination with a cam shaft, a carrier rod stopping nut and a spindle therefor, the latter having manually operable means, of a plurality of carrier rods, a mechanism for selectively engaging any one of said rods and displacing the same over the machine, means mounted upon said stopping nut and disposed for engagement with the carrier rods for locking the unselected carrier rods, said means being movable with said stopping nut through the manually operable means of the spindle for adjusting said locking means in relation to the carrier rods, and means controlled from the cam shaft and engaged with the spindle for actuating the latter independently of its manually operable means, thus automatically displacing the locking means together with the carrier rods held thereby for a distance of the length of travel of the carrier rod.

5. In a flat knitting machine the combination with a cam shaft, a carrier rod stopping nut and a spindle therefor, of a plurality of carrier rods, a mechanism for selectively engaging any one of said rods and displacing the same over the machine, means mounted upon said stopping nut and disposed for locking engagement with the carrier rods, and a mechanism between said cam shaft and said spindle for intermittently turning the latter first one way and then the other, thus automatically displacing the locking means together with the carrier rods held thereby back and forth for a distance of the length of travel of the selected carrier rod.

70 6. In a full-fashioned knitting machine having a plurality of carrier bars and a carrier bar selecting mechanism operable for selectively engaging and moving any one of said carrier bars its full width of travel, and for alternatively changing the selective engagement from one car-

rier bar to another at the end of each full movement whereby to form a series of courses each consisting of a separate individual thread, an additional mechanism operating conjointly with said first mentioned mechanism for engaging the unselected carrier bars and displacing the same for a part of their distance of travel simultaneously with the full movement of the selected carrier bar, and means for releasing the selected carrier bar for its full movement while retaining the unselected carrier bars.

7. In a full-fashioned knitting machine having a plurality of carrier bars and a carrier bar selecting mechanism operable for selectively engaging and moving any one of said carrier bars its full width of travel, and for alternatively changing the selective engagement from one carrier bar to another at the end of each full movement whereby to form a series of courses each consisting of a separate individual thread, an additional mechanism operating conjointly with said first mentioned mechanism for engaging the unselected carrier bars and displacing the same for a part of their distance of travel simultaneously with the full movement of the selected carrier bar, means for releasing the selected carrier bar for its full movement while retaining the unselected carrier bars, and means maintaining said retained unselected carrier bars in stationary position at the end of their partial movement while the released selected carrier bar continues to the end of its full distance of travel.

8. In combination with a row of loop forming needles and a plurality of thread carriers of a full-fashioned knitting machine, a mechanism operable to selectively and alternatively engage each one of said thread carriers and traverse the engaged carrier over the entire number of needles for forming a series of successive courses, each consisting of a separate individual thread, means co-functioning with said mechanism to engage the unselected thread carriers and traverse the same over a limited number of end needles simultaneously with the traversing of the selected thread carrier over the entire number of needles, and means for releasing the selected thread carrier in its traverse over the entire number of needles while retaining the unselected thread carriers.

9. In combination with a row of loop forming needles and three thread carriers of a full-fashioned knitting machine, a mechanism mounted to reciprocate over said row of needles and operable to selectively and alternatively engage at ever movement of its reciprocatory motion one of the three thread carriers and traverse the engaged carrier over the entire number of needles whereby to provide a series of successive courses each consisting of a separate individual thread, means co-functioning with said mechanism to engage the unselected thread carriers and traverse the same over a limited number of needles at the opposite ends of the row simultaneously with the traversing of the selected thread carrier over the entire number of needles to form a complete course, whereby to interloop at the selvedge edges of the latter the thread forming the one course with the threads forming the preceding courses, and means for releasing the selected thread carrier in its traverse over the entire number of needles while retaining the unselected thread carriers.
